[57] CLAIM

The ornamental design for a container for collecting oil,
as shown and described.

DESCRIPTION

FIG. 1 is a front elevational view of a container for
collecting oil showing my new design;

FIG. 2 is a right side elevational view thereof, the left
side elevational view being a mirror image thereof;

FIG. 3 is a rear elevational view thereof;

FIG. 4 is a rear elevational view thereof, with the cover
removed;

FIG. 5 is a top plan view thereof;

FIG. 6 is a top plan view thereof, with the cover re-
moved; and,

FIG. 7 is a bottom plan view thereof.
